United States Patent Office

Des. 183,484
Patented Sept. 9, 1958

183,484

BUILDING BLOCK TOY

Raymond C. Gaston, Madeira, Ohio, assignor to The Chas. Wm. Doepke Manufacturing Company, Inc., Rossmoyne, Ohio, a corporation of Ohio

Application June 13, 1957, Serial No. 46,591

Term of patent 14 years

(Cl. D34—15)

Fig. 1

I claim:

The ornamental design for a building block toy, substantially as shown and described.
